TOWEL DISPENSING APPARATUS

Albert C. Grunwald, River Forest, Ill., assignor to
Steiner Sales Company, Salt Lake City, Utah,
a corporation of Utah

Application March 13, 1933, Serial No. 661,542

17 Claims. (Cl. 312—38)

This invention relates generally to improvements in an apparatus for dispensing toweling. The invention is embodied in a type of apparatus in which a loop of toweling is normally maintained outside of the cabinet, and in which clean toweling delivery and soiled toweling take-up are obtained as the result of pulling the toweling by the user. The invention, however, is not entirely limited to a particular type of toweling dispensing apparatus.

The invention particularly relates to soiled toweling take-up means for obtaining an accelerated soiled toweling take-up action after the clean toweling supply is exhausted or nearly exhausted. In the illustrated embodiment, a loop of toweling hangs below the cabinet in a visible and accessible position. When the clean toweling supply is exhausted or nearly exhausted, it is contemplated herein either to rapidly or otherwise obliterate the loop by operating an auxiliary soiled toweling take-up means, or by operating such a means to rapidly or otherwise take up the free end of the clean toweling which may hang below the cabinet after the toweling is no longer held by the clean toweling feeding rolls.

Objects of the invention are: to provide auxiliary means for rapidly or otherwise drawing soiled toweling into the case, said means being automatically operable when the supply of clean toweling is substantially exhausted and as a result of the pulling out of the clean toweling by the user; to provide a motor for operating said take-up means and of such form that energy can be stored therein by manual operation, by the attendant; and to provide means by which the take-up means is rendered inoperative as the result of a motive energy-storing operation and is rendered operative as the result of release of such stored energy.

Another object is to provide what may be termed a rack and gear operated ratchet mechanism by which soiled toweling take-up rolls are operated when a gear rack is moved in one direction, but not operated when the rack is moved in the opposite direction, and to provide a spring against the tension of which the rack is moved in non-roll-operating direction, with means engageable by the rack when the spring is substantially fully tensioned to render the feed rolls inoperative, and by which as the result of and at the beginning of rack movement under action of the spring, the rolls are rendered operative.

Features of the invention include, along with the broader ideas of means inherent in the dis-

closure, all details of construction which relate to the operation and control of the auxiliary soiled toweling take-up means, whether such means be used alone or in combination with other soiled toweling take-up means.

Objects, features and advantages of the invention will be set forth in the description of the drawings forming a part of this application, and in said drawings

Figure 1 is a vertical transverse section taken on line 1—1 of Figure 4, showing the mechanism positioned as when there is remaining a substantial supply of clean toweling, and with a normal amount of looped toweling accessible and visible;

Figure 2 is a vertical transverse section taken on line 2—2 of Figure 4, illustrating the driving mechanism for an auxiliary soiled toweling take-up means and controls related thereto, with the parts positioned in correspondence to those shown in Figure 1;

Figure 3 is a vertical section, the upper portion being taken on line 2—2 of Figure 4, and the lower portion on line 1—1 thereof, and showing the position of the parts after the auxiliary soiled toweling take-up means has completed its take-up operation;

Figure 4 is a plan section on line 4—4 of Figure 2 showing part of the motive means and control therefor;

Figure 5 is a vertical section on line 5—5 of Figure 2 illustrating the construction of the auxiliary take-up rolls and some of the related parts;

Figure 6 is a vertical section on line 6—6 of Figure 3 further illustrating the control for the motive means; and

Figure 7 is a fragmentary detail sectional view taken approximately on line 7—7 of Figure 4, showing the means for initiating automatic toweling take-up action.

This invention is herein shown as applied to a wall type toweling dispensing cabinet, but is applicable to other forms and types of toweling dispensing apparatus. Referring first to Figure 1: Numeral 1 indicates the outer casing of the cabinet. This casing is provided with the usual door 2 and has, in its bottom 4 and at the rear, an elongated slot 3 upwardly through which the toweling is drawn to be connected with the soiled toweling take-up roll, common to this type of cabinet. The front edge of this bottom 4 is spaced from the door to form an elongated slot 5 to permit the toweling to pass beneath the cabinet to hang therebelow in a position to be seen and to be grasped by the user. Attached to the rear wall of the casing is a bracket 6 which forms

part of a means for smoothing out the soiled toweling before it reaches the soiled towel roll.

Within the casing is an element, referred to herein as the swing housing. This housing is formed by two side plates 10-11, cross-connected at their lower portions by a plate 12 which forms a support for a roll of clean toweling 13. Suitably supported in these plates are the usual feed and take-up rolls respectively indicated at 14-15. A second horizontally disposed plate 18 cross-connects the side plates 10 and 11, and has a curved portion 19 which extends forwardly and upwardly to lie between the feed and take-up rolls. The swing housing thus formed is pivoted by suitable means indicated at 20, the pivot being arranged near the top of the outer casing 1.

This swing housing supports the major portion of the mechanism of the present invention. After the door 2 is opened, the housing can be swung outwardly to facilitate introduction of fresh toweling and/or removal of soiled toweling.

For holding the swing housing in its outermost position while loading and unloading, a prop arm 22 is pivoted to the plate 11 as shown, see Figure 2, and is notched to engage the forward edge of the bottom of the outer casing 1. Two such arms may be employed.

In cabinets of this general type, push-button or lever control means (not shown herein) is provided for locking the feed roll against further motion after a predetermined length of clean toweling has been pulled out by the user, and this lever or button must be pushed each time to release the roll to permit a length of clean toweling to be drawn out. Such mechanism forms no part of the present invention, but is mentioned to make it clear that the feed roll is not continually free for rotation.

After introduction of a roll of clean toweling 13, the clean toweling is first brought in front of and engaged with a trip bar 72 later described, is then engaged with the feed roll 14, and is then brought around a pinch roll 23, journaled in slots 24. This roll operates by gravity in a well known manner to press the toweling against the feed roll to obtain the proper frictional contact. The toweling is then brought downwardly in front of that portion of the clean toweling which engages the trip bar, and then through the slot 5 below the bottom of the casing, then upwardly to form the loop 25, and is then passed between the soiled toweling take-up means of this invention. This means includes a series of concentric feed rolls, see Figures 4 and 5, each indicated by numeral 29, mounted on a shaft 30 journaled in elements 31, attached to plates 10 and 11. These rolls are fluted and are preferably made of rubber. Cooperative with the rolls 29 is a single elongated roll 32 so mounted as to be moved into and out of feeding relation with the series of rolls 29. To this end, the roll 32 is journaled in a frame 35 which is swingably supported or pivoted as at 36 to the back wall of the casing 1.

By reference to Figures 1 and 3, the roll 32 will be seen respectively in inoperative and operative positions. The toweling, as before mentioned, passes between the rollers 29 and 32, and thence upwardly around a towel-smoothing edge 37 of plate 18, then around a curved smoothing surface of the bracket 6, then upwardly against a smoothing bar 38, thence to the soiled towel roll 39, which rests by gravity upon and is driven by the take-up roll 15.

In order to keep the fresh toweling roll 13 from

coming in contact with the auxiliary take-up rolls, there is provided a guard element 40 as a plate, pivoted as at 41 to the plates 10-11, and having a portion 42 extending downwardly between the clean towel roll 13 and the rolls 29 and 32 and engaging another guard plate 43 which is secured to the plate 12 and, extends rearwardly therefrom, and has curved finger-like portions 44 which lie between the rolls 29 and over and extend around the shaft 30. The rear edge of this guard plate 40 is engaged by the soiled toweling as it passes upwardly, and at a point between roll 32 and smoothing edge 37. The plate is so balanced that it normally assumes the guarding position in Figure 1, but so that after operation of the auxiliary take-up rolls it assumes the position shown in Figure 3 in which position it is held by the toweling.

The means for driving the auxiliary soiled towel take-up device, in this embodiment, comprises a sprocket wheel 50 fast on shaft 30, and a sprocket 51 journaled on stub shaft 52, see Figure 4, on plate 11 of the swing housing. The sprockets are connected by chain 53. Only a few of the chain links have been shown in the drawings. This sprocket wheel 51 is driven herein by what may be termed a rack-and-gear-operated ratchet mechanism. This mechanism includes a cluster providing a ratchet gear 54 and a spur gear 55, journaled on stub shaft 52. A ratchet pawl, indicated at 56, is pivoted to sprocket 51 or at least is movable therewith, and provides the means for connecting the disk 51 for rotation by the ratchet wheel of the rack-operated cluster.

In mesh with the spur gear 55 are the teeth of a rack 56. A power spring 60 is connected by one end by pin 61 to the upper portion of the rack, and at the opposite end as at 62 to the lower portion of plate 11. The rack is suitably slidably guided by suitable means 63, attached to the plate 11. This guide element is slotted downwardly from its top, as at 64, and the pin 61 engages the lower end 65 of the slot to limit downward movement of the rack under action of the spring 60. This lowermost position of the rack is shown in Figure 3, while the uppermost position of the rack is shown in Figure 2.

This rack-and-gear-operated ratchet mechanism provides means by which the rolls are operated when the rack is moved in one direction, that is by the spring, but not operated when the rack is moved in the opposite direction, that is as the spring is tensioned. As the rack is moved from the position shown in Figure 3 to the position shown in Figure 2, to store power, the ratchet wheel is moved in a direction away from the pawl 56 so that the sprocket wheel 51 does not move.

The rack is held in its upper position against the action of the spring by means of a latch mechanism which, in this instance, consists of a pivoted detent 67, see Figure 2, having a shoulder engaging the lower end of the rack as at 68. A pivoted trip lever 69 and the latch 67 have a kind of ball and socket engagement with one another, as indicated at 70, and when this trip is moved in the direction of the arrow shown in Figure 2, the latch is tripped (see Figure 3) to release the rack which is then rapidly moved downwardly by the spring to move the gear 51 in clockwise direction and correspondingly rotate the feed rolls 29 in the same direction to rapidly take up the soiled toweling and obliterate the loop, or, in case the toweling has been pulled so as to release it from the feed rolls, to draw the free pendant portion of the toweling into the cabinet.

The trip lever 69 is operated by a horizontally disposed bar 72, see Figure 4, one end of which engages the trip lever as at 73. When the bar is raised, the trip lever is moved in counter-clockwise direction and tripping takes place. Both before and after tripping, the latch element 67 is so held by the trip element 69 as to act as an auxiliary means for maintaining the meshed relation of the rack and gear.

Tripping is performed automatically when the clean toweling supply is substantially exhausted. There are a number of ways in which this can be accomplished. Referring to Figures 7 and 4: The end of the clean toweling is preferably turned over and sewed or hemmed to provide a tubular pocket 16 in which is secured as by sewing a piece of clothes-line rope 17, or a rod, having a diameter about that of a lead pencil. This rope is flexible and washable, and does not interfere with an ironing operation. It is also possible to put in an extra thick hem to take the place of this tripping device. There is no intention to be limited to the character of device used. For obtaining automatic tripping by the toweling, the door 2 is provided with means generally indicated at 74, in this case comprising a metal strip bent to provide a projection which extends inwardly toward and is opposed to the trip rod 72 to form a relatively narrow passage 74 through which the upwardly and downwardly traveling portions of the clean toweling pass. The diameter of the rope 17 is such that it cannot pass upwardly through the passage 74, and the result of continued pulling down on the clean toweling by the user is to cause this rope to raise the trip element 72 and trip the latch 67, and obtain a result indicated in Figure 3, that is a quick take-up of the loop 25 to the position shown.

The provision of means for automatically initiating tripping of the auxiliary soiled toweling take-up means is another and important feature of the invention.

Another important feature of this invention relates to means operable respectively as the result of an energy-storing, and an energy-releasing operation of the spring motor, to render the take-up means inoperative at the end of the energy-storing operation, and to render it operative, or condition it for operation, as the result of energy-releasing operation and, in this instance, at the beginning of this operation. This feed release is necessary where, as in the present embodiment, the invention is used in conjunction with another soiled-toweling take-up means, so that take-up by rolls 15-39 is not interfered with by rolls 29-32. For this purpose, the pivoted frame 35 which carries the roll 32 has an extension 75, see Figure 4. To this extension 15 is pivoted, as at 76, see also Figure 2, the lower end of a rod 77, said rod being suitably guided (see Figure 6) for vertical sliding motion by means 78 attached to the wall of casing 1. Thus the roll 32 and rod 77 are not movable with the swing housing. This rod has a horizontal extension 80 which lies in the path of movement of the top end of the rack 56 and is so engaged by the upper end of the rack, as it approaches its limit of upward motion, that by the time the rack reaches its uppermost position, the element 77 is moved so that roller 32 assumes inoperative position, see Figure 1. The upward motion of the rack is limited by engagement of its upper end with a stop 81 of plate 11, see Figure 6. Thus, at the end of or during an energy-storing motion of

the rack, or of some element which assumes a predetermined position after or during such motion, the feed means is rendered inoperative.

Means is provided, accessible to the attendant, for moving the rack upwardly to put the spring under tension, and in this case comprises a cord or wire 83 attached at one end to the pin 61 and supported on two pulleys 84-85. The cord hangs from pulley 85 adjacent the front side of the casing 1 and has on its bottom end a ring 86 through which the finger or fingers of the operator can be engaged. By means of the ring, the cord is caused to move the rack upwardly from the position shown in Figure 3 to the position shown in Figure 2, this operation being generally performed after loading the cabinet with a fresh supply of clean toweling. As before stated, the rack is held in its uppermost position with the spring under tension by means of detent 67, and the auxiliary take-up means is rendered inoperative after the energy-storing operation.

General operation

Assume the parts positioned as in Figure 3, in which the latch has been tripped by the attendant and the remaining toweling drawn to the position shown to obliterate the loop. The attendant pulls downwardly on the remaining clean toweling to release it from the feeding and pinch rolls 14-23. He then pulls downwardly on the ring 86 to bring the rack to latched position, thus performing the energy-storing operation and moving the roll 32 to a position to release the soiled toweling. He now takes up the soiled toweling by rotating roll 15. He then introduces a roll of clean toweling and operatively associates the clean toweling with the various rolls as in Figure 1. He then moves the swing housing to the position shown in Figure 1, and the machine is thus conditioned for the regular toweling dispensing and take-up operation. Throughout this operation and until the latch is tripped, the roll 32 remains in inoperative position.

There is no intention to limit the present invention only to the use of a loop, since the device may be used to draw the terminal pendent portion of the toweling out of sight within the cabinet after the end of the toweling has been pulled out of the cabinet. It is further understood that the take-up mechanism of this invention can be made to act at more rapid, or at slower speeds, and that in some instances, the power for operating the take-up means may differ from that disclosed. Other motive means for automatically or manually operating the take-up may be used. However, the idea of a manually controlled operation, for both storing and releasing power, is claimed both in relation to an auxiliary feeding toweling take-up means, as distinguished from the operation of the main or normal soiled toweling take-up means which is operated in synchronism with the toweling feeding means or with the feed roll 14, and in relation to any soiled toweling take-up means.

Among other things, I therefore, broadly claim the use of an auxiliary soiled toweling take-up means which is independent of any means associated with the synchronized feeding and soiled toweling take-up means ordinarily used in this kind of device.

I claim as my invention:

1. In a toweling dispensing device of the type in which there is means to take up soiled toweling as clean toweling is pulled out by the user, aux-

iliary soiled toweling take-up means and driving means therefore including manually controllable means movable and operable for respectively storing and releasing energy, and means for releasably securing the movable means in energy-stored position.

2. In a towel dispensing device of the type in which there is means to take up soiled toweling as clean toweling is pulled out by the user, auxiliary soiled toweling take-up means and driving means therefor including means movable and operable for respectively storing and releasing energy, and means by which as a result of energy-storing motion of said movable means the take-up means is rendered inoperative, and by which as a result of energy-releasing motion thereof the take-up means is rendered operative.

3. In a towel dispensing device of the type in which there is means to take up soiled toweling as clean toweling is pulled out by the user, auxiliary soiled toweling take-up means and driving means therefor including manually controllable means movable and operable for respectively storing and releasing energy, means by which as a result of energy-storing motion of said movable means the take-up means is rendered inoperative, and by which as a result of energy-releasing motion thereof the take-up means is rendered operative, and means for releasably securing the movable means in energy-stored position.

4. In a towel dispensing device of the type in which there is means to take-up soiled toweling as clean toweling is pulled out by the user, auxiliary soiled toweling take-up means and driving means therefor, including a driving spring and means movable respectively for tensioning and releasing the spring and means by which as a result of tensioning motion of said movable means the take-up means is rendered inoperative, and by which as a result of releasing motion the tape-up means is rendered operative, and releasable means for holding said movable means in spring-tensioned position.

45 5. In a towel dispensing apparatus, a pair of cooperative soiled-toweling take-up rolls, between which the toweling passes, one roll being movable relative to the other driving means for said rolls including means movable respectively for storing and releasing energy, means by which as a result of energy-storing motion, the movable roll is moved to prevent take-up action, and by which as a result of energy releasing motion said roll is moved to permit take-up action.

55 6. In towel dispensing apparatus having means for normally taking up soiled toweling as clean toweling is pulled out by the user, auxiliary means for taking up said toweling after the supply of clean toweling is exhausted or substantially exhausted, means for driving said auxiliary take-up means including a spring controlled motor, means movable for putting the spring under tension for storing energy to operate the motor, means by which as a result of energy-storing motion, the take-up means is rendered inoperative, and by which as a result of energy-releasing motion, the take-up means is rendered operative, and releasable means for holding said movable means in energy-stored position.

70 7. In a towel dispensing apparatus a pair of rolls for taking up soiled toweling, means by which one of the rolls is moved to and from feeding relation with the other, driving means for one of the rolls including means movable respectively for storing and releasing energy,

means by which as a result of energy-storing motion of said movable means the roll-moving means is actuated to move its roll from feeding position and by which as a result of energy-releasing motion, the roll is moved to feeding position.

8. In towel dispensing apparatus having means for normally taking up soiled toweling as clean toweling is pulled out by the user, auxiliary means for taking up soiled toweling after the supply of clean toweling is exhausted or nearly exhausted including a pair of take-up rolls, driving means for said rolls including a rack-and-gear-operated ratchet mechanism by which the rolls are operated when the rack is moved in one direction, but not operated when moved in the opposite direction, a power spring against the tension of which the rack is moved in non-roll-operating direction, means engageable by the rack when the spring is substantially fully tensioned to render the feed rolls inoperative, and by which as a result of movement of the rack under action of the spring said rolls are rendered operative, and means for releasably securing the rack in spring-tensioned position.

9. In a towel dispensing apparatus, means for taking up soiled toweling, comprising a pair of take-up rolls, driving means for said rolls including a rack-and-gear-operated ratchet mechanism by which the rolls are operated when the rack is moved in one direction, but not operated when moved in the opposite direction, a power spring against the tension of which the rack is moved in non-roll-operating direction, means engageable by the rack after the spring is fully tensioned to render the feed rolls inoperative, and by which as a result of movement of the rack under action of the spring, said rolls are rendered operative, and means for releasably securing the rack in spring-tensioned position.

10. In a towel dispensing apparatus, means for taking up soiled toweling and driving means therefor including a rack-and-gear-operated ratchet mechanism by which said take-up means is operated when the rack is moved in one direction, but not operated when moved in the opposite direction, a power spring against the tension of which the rack is moved in non-take-up means-operating direction, and means for releasably securing the rack in spring-tensioned position, and means controlled by the toweling for tripping the rack-securing means to obtain soiled towel take-up.

11. In a towel dispensing apparatus, means for taking up soiled toweling and driving means therefor including a rack-and-gear-operated ratchet mechanism by which said take-up means is operated when the rack is moved in one direction, but not operated when moved in the opposite direction, a power spring against the tension of which the rack is moved in non-take-up means-operating direction, and means engageable by the rack after the spring is tensioned to render the take-up means inoperative, and by which as a result of movement of the rack under the action of the spring said take-up means is rendered operative.

12. In a towel dispensing device in which there is means to take up soiled toweling as clean toweling is pulled out by the user, auxiliary soiled toweling take-up means and driving means therefor including means movable and operable for respectively storing and releasing energy, means for releasably securing the movable means in energy-stored position, and means operable as a

result of pulling out of clean toweling by the user for operating said securing means to obtain release of the movable means and obtain operation of auxiliary take-up means.

5 13. In a towel dispensing device having soiled toweling take-up means and driving means therefor, means movable and operable for respectively storing and releasing energy, means for releasably securing the movable means in energy-stored 10 position, and means automatically operable as the result of pulling of the toweling by the user to move said releasable means to obtain energy release.

14. In towel dispensing device of the type in 15 which there is means to take up soiled toweling as clean toweling is pulled out by the user, auxiliary soiled toweling take-up means and driving means therefor, means movable and operable for respectively storing and releasing energy, means 20 for releasably securing the movable means in energy-stored position, and means automatically operable as the result of pulling of the toweling by the user to move said releasable means to obtain energy release.

25 15. A towel dispensing device of the type in which there is means to take up soiled toweling as clean toweling is pulled out by the user, auxiliary soiled toweling take-up means and driving means therefor including means movable and 30 operable for respectively storing and releasing energy, means which as a result of energy-storing motion of said movable means renders the auxiliary take-up means inoperative, and which as a result of energy release motion renders the auxiliary take-up means operative, and means controlled by the toweling for obtaining energy

release motion, to operate the auxiliary take-up means.

16. In towel dispensing apparatus of a type in which there is means to take up soiled toweling as clean toweling is pulled out by the user, auxiliary soiled toweling take-up means comprising a pair of rolls cooperative to feed the towel, one of the rolls being movable to and from feeding position, driving means for one of the rolls, means movable and operable for respectively storing and releasing energy, means for releasably securing the movable means in energy-stored position, means by which the movable roll is moved to inoperative position when said movable means is moved to energy-stored position, and means automatically operable as a result of pulling of the toweling by the user to move said releasable means to obtain energy release, such release acting on said roll-moving means to move said roll to feeding position.

20 17. In a towel dispensing device of the type in which there is means to take up soiled toweling as the clean toweling is pulled out by the user in which a visible loop of toweling is maintained including a soiled towel take-up roll, an auxiliary soiled towel take-up means adapted to act on the toweling at a point between the clean toweling and said take-up roll, and driving means therefor including means movable and operable for respectively storing and releasing energy and means which as a result of energy storing motion of said movable means the auxiliary take-up means is rendered inoperative by which as a result of energy release motion, said auxiliary take-up means is rendered operative, and means for obtaining energy release motion.

25 30 35 ALBERT C. GRUNWALD.
